UNITED STATES PATENT OFFICE.

ROBERT H. ALLWORK, OF NEW YORK, N. Y.

FLAT-TOP ROLL-COVER DESK.

1,421,357.

Specification of Letters Patent.

Patented July 4, 1922.

Application filed October 24, 1921. Serial No. 509,944.

To all whom it may concern:

Be it known that I, ROBERT HENRY ALLWORK, a citizen of the United States, residing at New York, in the county and State of New York, have invented new and useful Improvements in Flat-Top Roll-Cover Desks, of which the following is a specification.

This invention relates to desks, and my improvements are directed to means in conjunction with flat top desks whereby they may be convertible into roll top desks for closure purposes, while possessing the advantage of having an unincumbered, plain top surface, for all useful purposes.

The flat top desk has so largely superseded the roll top desk mainly because it provides a greater available surface area, besides having no superstructure to obstruct the view; but it is deficient in that no means have been provided to cover up or enclose the papers and other articles which may be left upon its surface at night or when the user is away.

Therefore my invention consists in the provision of a disappearing cover for flat top desks which is of articulate form and may be conveniently operated to cover up and enclose the desk top surface, and, when out of use, may be completely hidden from view.

My invention further consists in counterbalancing the weight of the disappearing cover in such manner that it can be drawn from its place of concealment within the desk structure, for enclosing purposes, with a minimum of effort, and return with equal facility.

Other features and advantages of my invention will hereinafter appear.

In the drawing:

Figure 1 is an end, sectional elevation of a desk provided with my improved disappearing top closure means.

Fig. 2 is a front sectional elevation of the same,

Fig. 3 is a side elevation of my improved desk, with the roll cover closed, and

Fig. 4 is an enlarged sectional detail of the pivotal mount for a gear.

In said views let 1 indicate the legs of a desk, 2 its flat top, 3 the rear panel, 4, 4, the side or end panels, 5, 5, lower stringers or frame members extended between front and rear legs, and 6, 6, upper frame members.

A shaft 7 extends lengthwise of the desk, beneath top 2, centrally thereof, and is

mounted in opposite end supports, here shown as bushings or bearings 8 in the respective end frame portions 6, 6, of the desk. The shaft ends each have a disk 9 secured thereto of larger diameter than the shaft, to lie against the end of bushing 8 and prevent withdrawal of the shaft, and caps 10 are provided to enclose the shaft ends, these caps being secured to the outer surface of the desk ends.

Fast upon the shaft 7, near its respective ends, are pinions 11, 11, to which are respectively secured, as by bolts 12, the cover end segments 13, 13, that each lie just inside an end panel 4, being entered respectively within vertical slots 14, 14, in the desk top. The segments 13 serve as side walls for a desk cover whose upper portion is in the form of a flexible apron composed of the slats 15 mounted on canvas 16 which bridges the segments and is secured to the edges thereof.

In Fig. 2 the segments 13, 13, are shown in full lines as sunk or disappeared within the desk, in which position they present their straight, flat edges flush with the upper surface of the desk top. It will further be seen, in Fig. 1, that the flexible apron is secured to the segments 13 only about a limited rearward extent thereof, as down to the point 17, the slack of the apron hanging between point 17 and point 19 where its other end is secured to the rear upper frame member 20. Thus the apron is held, when not in use, at the rear of the desk structure, so as not to interfere with drawers which may be fitted in the desk in the usual manner.

The flexible apron has a forward portion 21 which lies within a rear slot 22 in the desk top when the segments are sunk within the desk, the edge 21^a of portion 21 then lying flush with the upper surface of the desk top. But when the segments 13 are rocked through a half revolution, to bring them to a position above the desk, as end closure members, then the apron, including the slack portion, is carried over the desk top, as shown by the dotted lines in Fig. 1, and then the edge 21^a of portion 21 closes against the upper surface of the desk top, at its forward portion, thereby constituting a semi-circular cover for the desk top.

In order to counterbalance the weight of the cover and thus facilitate the operation of rocking the segments 13 and drawing

the apron up and over the desk top, as a closure therefor, I provide gears 23, 23, which are respectively meshed with the pinions 11, 11. The gears 23, 23 are respectively journaled in bars 24, 24 one at each side of the desk, these bars being here shown as connected to the frame portions 5 from which they extend upwardly. The bars 24 at their upper ends are each provided with apertures to receive the shaft 7, and means are provided whereby the bars 24 serve as aligning devices for the pinions 11 and gears 23, to maintain their meshed relation. Thus, the pinions 11 are each shown as having a hub 25 in thrust bearing relation with a bar 24, and the gears are held in alignment by the following means. A stud 26, which serves as a pivotal axis for a gear 23, has a reduced end portion 27 which is engaged with a bar 24, the gear and bar being laterally confined by means of a screw 28 entered axially within stud 26, the head of the screw being the confining means at one side, and the head of the stud being the confining means at the other side.

Intermediate the gear 23 and bar 24 the stud 26 carries an arm 29, which is secured to the gear 23 as by screws 30. The purpose of the arms 29 is to carry weights 31 which balance the weight of the flexible cover; and in order that the balancing may be accurate each weight 31 is adjustable lengthwise of its arm 29, and provided with a set screw 32 for securing it in its adjusted position.

The gear 23 is provided with opposite arcuate slots 23^a, in which are respectively entered headed studs 24^a that extend from the bar 24; the slots 23^a permitting oscillatory movement of gear 23 over the studs 24^a, and the stud heads serving to maintain the gear 23 in meshed alignment with pinion 11.

The shaft 7 may be adjustable as to its length, for use with desks of different sizes, and is here shown as composed of two sections, with a connecting sleeve 33. Near each end, the shaft 7 is provided with a collar 34, with securing means, enabling the collar to be adjusted to form a thrust bearing coacting with a shaft-end disk 9, to localize the pinion 11, with segment 13, and bar 24, in their operative positions. The weights 31 are elevated when the apron is sunk within the desk structure, and are adapted to balance its weight. In the example illustrated, gears 23 have a two to one ratio with pinions 11, so that the half revolution of pinions 11, representing the full closing movements of segments 11 and the apron, is coincident with the fall of weights 31 during a quarter revolution of gears 23.

Variations within the spirit and scope of my invention are equally comprehended by the foregoing disclosure.

I claim:

1. The combination, with a flat top desk, whose top is provided with slots near each side edge and a rear slot, of a shaft journaled below the desk top, segmental walls respectively operable through the side slots and carried by the shaft, the segments each exceeding a half circle, and a flexible apron secured at one end to the segmental walls, the apron adapted to be drawn through the rear slot and over the segmental walls in their rotation, to cover the desk top.

2. The combination, with a flat top desk whose top is provided with slots near each side edge and a rear slot, of a shaft journaled below the desk top, segmental walls, each exceeding a half circle, respectively operable through the side slots and carried by the shaft, and a flexible apron fastened at one end to the segmental walls and at its other end to the desk structure, the apron adapted to be drawn over the segmental walls in their rotation, to cover the desk top.

3. The combination, with a flat top desk whose top is provided with slots near each side edge and a rear slot, of a shaft journaled below the desk top, segmental walls, each exceeding a half circle, respectively operable through the side slots and carried by the shaft, a flexible apron secured at one end to the segmental walls and adapted to be drawn through the rear slot and over the segmental walls, and means for counterbalancing the weight of the walls and cover, to facilitate their operation.

4. The combination, with a flat top desk, of a disappearing roll cover therefor having segmental side walls, a shaft engaging the side walls, fixed brackets revolvably supporting the shaft, pinions fastened to the shaft, gear wheels of greater diameter than the pinions mounted on the brackets and meshed with the pinions, arms extended from the gear wheels, and weights carried by the arms to counterbalance the cover.

5. The combination, with a flat top desk whose top is provided with slots near each side edge and a rear slot, of segmental walls, each exceeding a half circle, pivotally mounted respectively near the desk sides, below the top, and operable through the side slots, and a flexible apron secured at one end to the segmental walls, the apron adapted to be drawn through the rear slot and over the segmental walls in their rotation, to cover the desk top, and the bases of the segmental walls, with the forward end of the apron, respectively lying within and filling the side and rear slots, flush with the desk top, when the latter is exposed.

Signed at New York, in the county and State of New York, this 20th day of October, 1921.

ROBERT H. ALLWORK. [L.S.]
